UNITED STATES PATENT OFFICE.

ABRAHAM L. BROWN, OF ST. LOUIS, MISSOURI, ASSIGNOR TO MELLIER COMPANY, PEF-FUMER, OF ST. LOUIS, MISSOURI, A CORPORATION OF MISSOURI.

BOX.

No. 905,145.

Specification of Letters Patent.

Patented Dec. 1, 1908.

Application filed June 27, 1908. Serial No. 440,755.

To all whom it may concern:

Be it known that I, ABRAHAM L. BROWN, a citizen of the United States, residing at the city of St. Louis, State of Missouri, have 5 invented a certain new and useful Improvement in Boxes, of which the following is a specification, reference being had to the accompanying drawings, forming part of this specification, in which—

10 Figure 1 is a longitudinal sectional view through my improved box, showing the parts thereof as arranged when the box is closed and used as a storage or shipping receptacle; Fig. 2 is a similar view, showing the parts of 15 my box as arranged when the box is open and used as a vending receptacle; and Fig. 3 is a perspective view, partly in section, of my said box.

This invention relates to a new and useful 20 improvement in boxes, the object being to provide a box adapted to be used as a shipping, display, or vending receptacle, which is simple, made up of very few parts, easily manufactured, and at slight cost.

25 With this object in view, my invention consists in the novel arrangement and construction of the several parts of my box, all as will hereinafter be described and pointed out in the claims.

30 My box has heretofore been used by me in storing, shipping, displaying, and vending bottles of perfume, but it is obvious that my said box may be used for many and various purposes; and also, while I have shown my 35 box as rectangular in shape, it may be made of any shape or size desired.

As shown in the drawings, my box is made up of three parts, the body portion A, the top portion B, and bottom portion C.

40 The body portion A, as shown in Fig. 3, is made of four connected side walls, without top or bottom, forming an open retaining or surrounding casing or frame for the top B and bottom C, which are adapted to loosely 45 and slidably fit therein.

The top portion B consists of the portion or wall 1 and the four side walls 2 connected thereto, and the bottom C consists of the portion or wall 3 and the four side walls 4 connected thereto. The combined width or depth of side walls 2 of top B and side walls 4 of bottom C is substantially equal to the width or depth of the walls of body portion A, so that when said top B and bottom C 55 are in position within said body portion or

casing A, the portions or walls 1 and 3 of said top B and bottom C are on a level or substantially flush with the edges of said casing A, as shown in Fig. 3.

When the box is used as a storage or shipping receptacle, the top B and bottom C are placed within casing A as shown in Figs. 1 and 3, in which position the box is closed and the goods are adapted to be contained therein, an outer wrapper, not shown, being 60 preferably used to hold the casing A, top B, and bottom C together. When it is desired to display the goods in vending the same, as the top B and bottom C loosely fit in said inclosing casing A, no attaching means being 65 used, the parts of my box are easily disconnected, or the box is easily opened, by simply raising the casing A. In displaying the goods, either now the top B or bottom C is reversed, as shown in Fig. 2, and the casing A placed in position around the same, the bottom C or top B acting as a support for the other in displaying the goods. Depending upon the goods to be displayed, either top or bottom may be used to hold the 70 goods in displaying the same, simply by reversing the position of the said parts, as will be readily understood; and instead of having both top B and bottom C in open position 75 as shown in Fig. 2, when it is desired to display the goods, either the top or bottom alone may be turned to open position in order to display the goods therein, the other part, either top or bottom, remaining in closed position, when such latter part may 80 be used at the same time as a storage receptacle, but in whatever position the parts may be placed, the top or bottom acts as a supporting base for the other in displaying the 85 goods, as shown clearly in Fig. 2, the casing 90 A serving to hold said top and bottom in operative position.

It will thus be seen that my box is very simple, composed of few parts, and is cheap to manufacture, and the parts thereof are 100 easily manipulated in changing or reversing the several positions of the same, as above described. The depth or width of the walls 2 of top B and walls 4 of bottom C may be the same, or the depth of walls 2 may be 105 greater than the depth of walls 4, as shown herein, depending upon the uses to which the box is put and so that the goods may be properly displayed when the box is opened. As shown in Fig. 3, the portion 1 of top B 110

and the walls of casing A may be ornamented, if desired, to add to the attractiveness of the box, the box being adapted to be placed in or upon a show-case or other suitable place when the box is used as a display or vending receptacle. When the box is used as a storage or shipping receptacle, the edges of the walls 2 of top B and of walls 4 of bottom C are adapted to meet within the inclosing casing A, whereby a neat and compact, closed box is provided.

Having thus described my invention, what I claim and desire to secure by Letters Patent is:

- 15 1. A box consisting of an inclosing frame and top and bottom portions loosely and reversibly fitting therein; substantially as described.
- 20 2. A box consisting of an inclosing frame and top and bottom portions loosely and reversibly fitting therein, said top or bottom portions being adapted to support the other within said frame; substantially as described.
- 25 3. A box consisting of an inclosing frame composed of four connected side walls, a top consisting of a portion 1 and four side walls connected thereto, and a bottom composed of a portion 3 and four side walls connected thereto, said top and bottom being adapted

to loosely and reversibly fit in said frame; substantially as described.

4. A box consisting of an inclosing frame composed of four connected side walls, a top consisting of a portion 1 and four side walls 35 connected thereto, and a bottom composed of a portion 3 and four side walls connected thereto, said top and bottom loosely and reversibly fitting in said frame and the combined depth of the side walls of said top and bottom being substantially equal to the depth of the walls of said frame; substantially as described.

5. A box consisting of an inclosing frame composed of four connected side walls, a top 45 consisting of a portion 1 and four side walls connected thereto, and a bottom composed of a portion 3 and four side walls connected thereto, said top and bottom loosely fitting in said frame and said frame being slidably 50 removable from around said top and bottom; substantially as described.

In testimony whereof, I have signed my name to this specification, in the presence of two subscribing witnesses.

ABRAHAM L. BROWN.
